CLOCK

Joseph Maluo, Honolulu, Territory of Hawaii

Application April 5, 1940, Serial No. 328,130

4 Claims. (Cl. 58—125)

My invention relates to amusement devices and more particularly to improvements in clocks.

The principal object of my invention is to provide a simply constructed, inexpensive, clock for use in a projecting machine, such as a moving picture projector, to project the time on a screen in a novel manner, and which is equipped for manual control to start and stop the same at will.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in front elevation of the preferred embodiment of my improved clock,

Figure 2 is a view in transverse section taken on the line 2—2 of Figure 1,

Figure 3 is a view in vertical section taken on the line 3—3 of Figure 2, and

Figure 4 is a detail view in vertical transverse section taken on the line 4—4 of Figure 3.

Referring to the drawings by numerals, the illustrated embodiment of my improved clock comprises a cylindrical shell 1 of any suitable size and material having a pair of annular front and rear disks 2, 3, of plate-like form detachably secured in opposite sides thereof, respectively, the shell 1 being rabbeted, as at 4, to seat the outer edges of the disks 2, 3, and grooved, as at 5, to receive resilient keeper rings 6 for retaining said disks in place. The disks 2, 3, may be formed of any suitable transparent material such as glass, mica, or the like.

A pair of front and rear plates, 7, 8, of circular form and suitable opaque material are fitted in the openings of the disks 2, 3, respectively, said plates having rabbeted edges 9 adapting the same to fit against the disks 2, 3, and overlap the outer faces of the latter. A pair of front and rear clamping plates 10, 11, of the same size as the plates 7, 8, are opposed to the latter, respectively, concentrically thereof and against the inner faces of the same in overlapping relation to the inner faces of the disks 2, 3, respectively. Elongated screws 12 connect the plates 7, 8, at suitable points and spacing sleeves 13 on said screws and extending between the plates 10, 11, hold the latter in clamping relation to the disks 2, 3.

The front disk 2 has suitably delineated thereon inner and outer annular dials 14, 15, sur-

rounding the front plate 7 concentrically thereof and relative to each other. The inner dial 14 is graduated and numbered for seconds, and the outer dial 15 graduated and numbered for hours and minutes.

Hour and minute hands 17 and 16 are mounted in front of the disk 2 and plate 7 for movement over the dials 15 and 14, respectively, as follows.

Journalled at its front end in the front plates 7, 10, axially thereof is a hollow hour hand arbor 18 extending into the shell 1 for a suitable distance and having the hour hand 17 secured on the front end thereof. Intermediate the ends thereof said arbor 18 is also journalled in a bracket 19 having a U-shaped part 20 suitably secured to the rear face of the front clamping plate 10 to extend rearwardly therefrom at one side of the arbor 18, and a laterally bent arm 21 extending diametrically of the shell 1 and in which said arbor 18 is journalled. The arm 21 terminates on the opposite side of the arbor 18 in a bearing socket 22 for a purpose presently seen. The purpose of the U-shaped part 20 will presently be explained.

Extending through the hour hand arbor 18 and rotatable therein is an arbor 23 for the minute hand 16, the latter being fast on the front end thereof. The rear end of the arbor 23 has a needle bearing 24 in the rear clamping plate 11.

The arbors 18 and 23 are rotated by the following clockwork mechanism. Journalled at one end in the U-shaped part 20 of bracket 19 and extending diametrically of the shell 1 is a short shaft 25 to which one end of a convolute clock spring 26 is fixed, the other end of said spring being suitably secured to a circular casing 26' enclosing said spring and rotatably mounted on said shaft 25 to be revolved about the same by the spring. A drive gear 27 is fixed on one side of the casing 26' in mesh with a suitably smaller gear 28 fast on one end of a driven shaft 29 journalled in a bearing bracket 30 fixed to the inner face of the rear clamping plate 11 and extending diametrically in the shell 1. A friction wheel 31 fast on the other end of the driven shaft 29 engages one side of a larger friction wheel 32 fast on the inner end of the second hand arbor 23. On the opposite side of the arbors 18, 23, from the clock spring 26 and casing 26' is a drive shaft 33 for the hour hand arbor 18 extending parallel with said arbor and having needle bearings 34 in the socket 23 and the bracket 30. A bevelled edge friction wheel 35 is fixed on said shaft 33 in edge engagement with a peripheral

groove 36 in the friction wheel 32. A second friction wheel 37 suitably smaller than the wheel 35 is fixed on shaft 33 in peripheral engagement with a peripherally grooved friction wheel 38 fast on the arbor 18.

A ratchet wheel 39 fast on the shaft 25 and a holding dog 40 on the bracket 19 provide for holding the shaft 25 against rotation during unwinding of the spring 26. The outer end of the shaft 25 has a radial stud 41 thereon for attaching a suitable winding key to said shaft as shown in dot and dash lines at 42 in Figure 3, an opening 43 being provided in the shell 1 for the extension of said key into said shell. Means for manually controlling the spring and described clock works are provided in the form of a manually operative escapement as follows. Fast on the gear 27 is a second, escapement ratchet wheel 44 engaged by an escapement dog 45 which in turn is fast on the inner end of an escapement key 46 extending diametrically into the shell 1 parallel with shaft 25 with its outer end journalled in said shell and its inner end journalled in bracket 19. A coil spring 47 suitably connected to the key 46 and bracket 19 serves to urge the key in a direction to swing the escapement dog 45 into engagement with the escapement ratchet wheel 44. The hands 16, 17, are provided with eyelet-like outer ends 48 through which the graduations and numbers on the hour dial 15 and seconds dial 14 may be viewed.

The operation of the described clock will be readily understood. With the spring 26 wound, the hands 16, 17, preset, and upon the release of the described escapement by manipulation of the escapement key 46 in the proper direction to disengage the escapement dog 45 from the escapement ratchet wheel 44, the hour and minute hands 17, 16, will be driven through the described clockworks mechanism in the relative ratio of the speed usual in ordinary clocks.

Upon arrangement in a projector, not shown, in proper position relative to the lens of said projector, the image of the dials 14, 15, and the outer ends 48 of the hands 16, 17, may be projected onto a screen to indicate any desired time, it being understood that as soon as the escapement key 46 is released, the escapement dog 45 will engage the escapement ratchet wheel 44 and stop the clock.

As will be understood, the described clock is designed to be used to flash the time on a screen for short intervals, only, in contests in which the audience takes part as holders, for instance, of time indicating tickets, or, in the playing of games, in which an audience takes part, different time intervals being of the essence of the game. As one example of the use of the clock, the distributed tickets may have delineated thereon the dials of the clock and the hands arranged for indicating different time on each ticket. The clock may be started to operate for a selected interval and then stopped. A ticket holder whose ticket is timed in accordance with that indicated by the clock when stopped will be entitled to a prize.

The foregoing will, it is believed, suffice to impart a clear understanding of my invention without further explanation.

Manifestly the invention, as described, is susceptible of modification without departing from the inventive concept, and right is herein reserved to such modifications as fall within the scope of the subjoined claims.

What I claim is:

1. A clock for use in an image projecting machine to project the time on a screen comprising a cylindrical shell having open ends, a pair of annular disks of transparent material secured in said shell at opposite ends thereof, respectively, one of said disks having delineated thereon a pair of inner and outer annular dials arranged thereon concentrically thereof, one of said dials being an hour and minutes indicating dial and the other a seconds indicating dial, a pair of opaque circular plates fitted in said disks, respectively, and secured therein, a rotatably mounted axial arbor of tubular form in said shell and having one end extended out of one of said plates forwardly of said dials, an hour hand fast on said end of said arbor for rotation thereby around said hour and minutes indicating dial, a second arbor rotatable in the tubular arbor and extending out of said one end of the same, a minutes hand fast on said second arbor for rotation thereby around said minutes indicating dial, and means in said shell to rotate said arbors and located between said plates to prevent interference with projection.

2. A clock for use in an image projecting machine to project the time on a screen comprising a cylindrical shell having open ends, a pair of annular disks of transparent material secured in said shell at opposite ends thereof, respectively, one of said disks having delineated thereon a pair of inner and outer annular dials arranged thereon concentrically thereof, one of said dials being an hour and minutes indicating dial and the other a seconds indicating dial, a pair of opaque circular plates fitted in said disks, respectively, and secured therein, a rotatably mounted axial arbor of tubular form in said shell and having one end extending out of one of said plates forwardly of said dials, an hour hand fast on said end of said arbor for rotation thereby around said hour and minutes indicating dial, a second arbor rotatable in the tubular arbor and extending out of said one end of the same, a minutes hand fast on said second arbor for rotation thereby around said minutes indicating dial, and means in said shell to rotate said arbors and located between said plates to prevent interference with projection.

3. A clock for use in an image projecting machine to project the time on a screen comprising a cylindrical shell having open ends, a pair of annular disks of transparent material secured in said shell at opposite ends thereof, respectively, one of said disks having delineated thereon a pair of inner and outer annular dials arranged thereon concentrically thereof, one of said dials being an hour and minutes indicating dial and the other a seconds indicating dial, a pair of opaque circular plates fitted in said disks, respectively, and secured therein, a rotatably mounted axial arbor of tubular form in said shell and having one end extended out of one of said plates forwardly of said dials, an hour hand fast on said end of said arbor for rotation thereby around said hour and minutes indicating dial, a second arbor rotatable in the tubular arbor and extending out of said one end of the same, a minutes hand fast on said second arbor for rotation thereby around said minutes indicating dial, and means in said shell to rotate said arbors and located between said plates to prevent interference with projection.

interference with projection, said means comprising a normally disabled spring motor, means to enable said motor at will, a motor driven shaft operable by said motor, and a friction drive between said shaft and said arbors.

4. A clock for use in an image projecting machine to project the time on a screen comprising a cylindrical shell having open ends, a pair of annular disks of transparent material secured in said shell at opposite ends thereof respectively, one of said disks having delineated thereon a pair of inner and outer annular dials arranged thereon concentrically thereof, one of said dials being an hour and minutes indicating dial and the other a seconds indicating dial, a pair of opaque circular plates fitted in said disks, respectively, and secured therein, a rotatably mounted axial arbor of tubular form in said shell and having one end extended out of one

of said plates forwardly of said dials, an hour hand fast on said end of said arbor for rotation thereby around said hour and minutes indicating dial, a second arbor rotatable in the tubular 5 arbor and extending out of said one end of the same, a minutes hand fast on said second arbor for rotation thereby around said minutes indicating dial, and means in said shell to rotate said arbors and located between said plates to 10 prevent interference with projection, said means comprising a normally disabled spring motor, means to enable said motor at will, a motor driven shaft operable by said motor, and a friction drive between said shaft and said arbors, 15 said enabling means including a releasable escapement, and an escapement releasing key extending out of said shell.

JOSEPH MALUO.
